UNITED STATES PATENT OFFICE.

DAVID F. VAUGHAN, OF HADDONFIELD, NEW JERSEY.

MEANS FOR SECURING RAILS.

No. 823,828.

Specification of Letters Patent.

Patented June 19, 1906.

Application filed January 29, 1906. Serial No. 298,411.

To all whom it may concern:

Be it known that I, DAVID F. VAUGHAN, a citizen of the United States, residing at Haddonfield, Camden county, New Jersey, have 5 invented certain new and useful Improvements in Means for Securing Rails, of which the following is a full, clear, and exact description, reference being had to the accompanying drawings, of which—

10 Figure 1 is a sectional elevation of a rail, a portion of a tie, and a rail-chair embodying my invention. Fig. 2 is a plan view thereof. Fig. 3 is a view similar to Fig. 1, including splice-bars for uniting two rail-sections and showing the chair designed to support the rail and engage the splice-bars. Fig. 4 is a plan view of Fig. 3. Fig. 5 is a perspective view of the rail-chair shown in Figs. 1 and 2. Fig. 6 is a perspective view of the rail-chair 15 shown in Figs. 2 and 3. Fig. 7 is a perspective view of that portion of the tie shown in Figs. 1, 2, 3, and 4.

This invention relates to metallic railway-ties and means for securing rails thereto.

20 The object of the invention is to provide a metallic railway-tie and rail-chair of simple and efficient construction having provision whereby the chair may be firmly secured to the tie and whereby the rail may be firmly 25 secured to the chair to effectually prevent displacement of the parts.

A further object of the invention is to provide for the adjustment of the parts to compensate for wear due to the great weight 30 passing over the rail.

The invention consists in the novel construction and combinations of parts herein-after fully described and claimed.

In the present embodiment of my invention 35 the tie is made in the form of an I-beam, comprising the vertical web 1 and the upper and lower flanges 2 and 3, respectively. The opposite edges of the upper flange 2 are provided with diagonally opposite recesses 4 40 therein.

45 Resting upon the tie between the recesses 4 is the rail-chair comprising the flat body portion 5, the upwardly-extending flanges 6, and the lateral projections 7. The body portion 5 and the vertical flanges 6 form a channel for the reception of the foot-flange 8 of the rail 11, and the edges of said foot-flange engage the inner walls of the flanges 6 to prevent lateral displacement of the rail upon the 50 chair. The flanges 6 are divided into sec-

tions by transverse vertical slots 9, and after the rail has been seated within the channel one or both sections of each flange 6 is swaged tight against the foot-flange 8 and bent over into engagement with the top thereof, thus 60 firmly securing the rail to the chair. The lateral projections 7 extend downwardly through the recesses 4 to form shoulders 10 and then horizontally beneath the flange 2, the shoulders 10 taking against the walls of 65 the recesses 4, and thus preventing displacement of the chair laterally of the rail 11 or longitudinally of the tie. The outer ends of the lateral projections 7 are provided with bolt-holes in line with similar holes in the superposed flange 2 for the reception of bolts 12, by means of which the chair is secured to the flange 2, said bolts assisting the shoulders 10 in preventing displacement of the chair 70 upon the tie.

75 In assembling the parts the chair is first placed upon the tie on an angle with respect thereto with the shoulders 10 opposite to the recesses 4. The chair is then turned to bring the shoulders 10 into the recesses 4 and into 80 engagement with the walls thereof. The foot-flange 8 of the rail 11 is then placed within the channel formed between the flanges 6, and one or both sections of each flange 6 is swaged against the foot-flange 8 85 and bent over into engagement with the top thereof. Thus it will be seen that the chair is locked in position by the edges of the foot-flange 8 engaging the inner walls of the flanges 6 and preventing the turning of the 90 chair to disengage the shoulders 10 from the recesses 4. The bolts 12 may now be applied to the flange 2 and projections 7 to more firmly secure the chair to the tie, or the bolts may be dispensed with, as desired. When 95 the bolts 12 are employed, I construct the chair so that the projections 7, extending beneath the flange 2, will not be quite parallel to said flange, as shown by dotted lines at the right-hand side of Fig. 1, whereby when the 100 bolts 12 are applied the projections 7 will be forced up against the bottom of the flange 2, thus increasing the tension or rigidity of the entire chair. I preferably form a channel or groove 13 in the body portion 5 at the base of the inner wall of each flange 6, to the end that the flanges 6 may be more tightly swaged into engagement with the foot-flange 8. Should any wear between the foot-flange 8 and the flanges 6 occur, due to the great 105 110

weight passing over the rail, and thereby loosen the rail upon the chair, the said wear may be compensated for by again driving or swaging the flanges 6 tight against the foot-flange 8, or if but one section of each flange 6 was previously bent into engagement with the foot-flange of the rail then the wear may be compensated for by bending the remaining sections of the flanges 6 into engagement with said foot-flange.

In Figs. 3, 4, and 6 I have shown the chair designed to support the rail at the meeting ends of two rail-sections where the usual splice-bars 14 are employed. In this case the chair is constructed the same as the chair shown in Figs. 1, 2, and 5, excepting that the vertical flanges 6 are arranged farther apart to receive and engage the edge of the foot of each splice-bar 14, similar to the manner in which they engage the edges of the foot-flange 8 of the rail, and excepting also that the base 5 is provided with upwardly-extending lugs 15, arranged to enter the usual spike-slot 16 in the foot of each splice-bar 14, and thus prevent longitudinal movement of the rail with respect to the chair. If desired, the splice-bars may be slotted wide enough to receive the flanges 6 adjacent to the edges of the foot-flange 8 of the rail 11, in which event it will be seen that the same chair may be used in connection with splice-bars as elsewhere, no special width of channel then being necessary. Further, when the splice-bars do not extend over and beyond the foot-flange of the rail the same chair may be used in connection with the splice-bars as elsewhere. The chairs may be forged or may be formed from a suitably-rolled section. In the latter case the vertical flanges 6, forming the chair for the reception of the rail 11, would extend the full width of the chair, the lateral projections 7 being formed by suitable flanges originally rolled on the section and then cut away to form the projections 7, as shown in the drawings.

I claim—

1. The combination of a tie having an upper flange the opposite edges of which are provided with diagonally opposite recesses, a chair resting upon the tie and engaging the walls of said recesses, and a rail secured to said chair.

2. The combination of a tie having an upper flange the opposite edges of which are provided with diagonally opposite recesses, a chair provided with a channel and resting upon the tie and engaging the walls of said recesses, and a rail secured to the chair within the channel thereof.

3. The combination of a tie having an upper flange, the opposite edges of which are provided with diagonally opposite recesses, a chair provided with a channel and resting upon the tie and engaging the walls of said recesses, and a rail resting upon the chair with-

in the channel thereof, said channel having portions of its walls bent into engagement with the top of the foot-flange of the rail.

4. The combination of a tie having an upper flange provided with diagonally opposite recesses, a chair resting upon the tie and provided with projections extending through said recesses and engaging the walls thereof and engaging the bottom of said flange, and a rail secured to said chair.

5. The combination of a tie having an upper flange the opposite edges of which are provided with diagonally opposite recesses, a chair provided with a channel and projections extending through said recesses and engaging the walls thereof and engaging the bottom of said flange, and a rail secured to said chair within said channel.

6. The combination of a tie having an upper flange provided with diagonally opposite recesses, a chair resting upon the tie and provided with a channel and projections extending through said recesses and engaging the walls thereof and the bottom of said flange, and a rail secured to said chair within the channel thereof, said channel having portions of its walls bent into engagement with the top of the foot-flange of the rail.

7. The combination of a tie having an upper flange the opposite edges of which are provided with diagonally opposite recesses, a chair resting upon the tie and provided with projections extending through said recesses and engaging the walls thereof and the bottom of said flange, means for securing said projections to said flange, and a rail secured to said chair.

8. The combination of a tie, a rail, and a chair secured to the tie and comprising a base upon which the rail is seated and vertical flanges engaging the edges of the foot-flange of the rail, said flanges being slotted to divide them into sections and sections of said flanges being bent into engagement with the top of the foot-flange of the rail.

9. The combination of a tie, a rail, and a chair secured to the tie and comprising a base upon which the rail is seated and vertical flanges engaging the edges of the foot-flange of the rail, said base being provided with a groove at the base of the inner wall of each flange, and portions of said flanges being bent into engagement with the top of the foot-flange of the rail.

10. The combination of a tie, a rail, and a chair secured to the tie and comprising a base upon which the rail is seated and vertical flanges engaging the edges of the foot-flange of the rail, said base being provided with a groove at the base of the inner wall of each flange, said flanges being slotted to divide them into sections and sections of said flanges being bent into engagement with the top of the foot-flange of the rail.

11. The combination of a tie, having an

upper flange provided with a recess therein, a chair, resting upon the tie and engaging the wall of said recess, a rail resting upon the chair, a splice-bar secured to the rail and having a slot therein, and a projection on said chair engaging the walls of said slot to prevent longitudinal movement of the rail upon the chair.

12. The combination of a tie, a chair secured thereto and provided with a channel, a rail resting upon the chair within the channel thereof, a splice-bar secured to the rail and having a slot therein, and a projection on said chair engaging the walls of said slot to prevent longitudinal movement of the rail upon the chair.

13. The combination of a tie, a chair secured thereto and provided with a channel, a rail resting upon the chair within the channel thereof, a splice-bar secured to the rail and having a slot therein, and a projection on said chair engaging the walls of said slot to prevent longitudinal movement of the rail upon the chair, said channel having portions of its walls bent into engagement with the top of the foot of the splice-bar. 20

In testimony whereof I have hereunto affixed my signature.

DAVID F. VAUGHAN.
